UNITED STATES PATENT OFFICE.

REUBEN BINKOVITZ, OF BROOKLYN, NEW YORK, ASSIGNOR TO M. BINKOVITZ & SONS INC., OF NEW YORK, N. Y., A CORPORATION OF NEW YORK.

DESIGN FOR A MATTRESS TICKING OR SIMILAR ARTICLE OF MANUFACTURE.

Application filed October 9, 1928. Serial No. 28,414. Term of patent 7 years.

To all whom it may concern:

Be it known that I, REUBEN BINKOVITZ, a citizen of the United States, residing in the borough of Brooklyn, county of Kings, city and State of New York, have invented a new, original, and ornamental Design for Mattress Ticking or Similar Article of Manufacture, of which the following is a specification, reference being had to the accompanying drawing, forming part thereof.

The drawing is a face view of a portion of a strip of mattress ticking representing the width of the fabric and illustrating the design, which is repeated indefinitely through-

out the length of the strip. In the drawing the design has been completed only in the upper portion of the view, but it will be understood that in the article the design is continued throughout the length of the strip.

A unit of the design is included between the lines A—A and B—B, this unit being repeated indefinitely throughout the length of the strip.

I claim:

The ornamental design for a mattress ticking or similar article of manufacture, substantially as shown and described.

REUBEN BINKOVITZ.
